CARPET SWEEPER

Fred W. Pullen, Grand Rapids, Mich., assignor to
Bissell Carpet Sweeper Co., Grand Rapids,
Mich.

Application January 8, 1932, Serial No. 585,421

9 Claims. (Cl. 15—41)

The objects of the invention are:

First, to provide an improved spring structure for applying pressure to the wheels in the broom action.

Second, to provide in such a structure an improved arrangement of equalizing means for the spring and floor wheels.

Third, to provide such a structure which can be made as a unitary device for attachment to the end of a carpet sweeper case.

Further objects and objects relating to details will appear from the description to follow.

A preferred embodiment of my invention is illustrated in the accompanying drawing, in which:

Fig. 1 is an end elevation of a carpet sweeper embodying the features of my invention, the buffer band and bumper corners being omitted.

Fig. 2 is an elevation view of the detached spring and equalizer unit looking from the inside out, the floor wheels being omitted.

Fig. 3 is a detail plan view of the unitary structure with the wheels present.

Fig. 4 is a detail plan view of the end bar, the spring support and slideway, the spring, the slide, the equalizing levers, journal pins, fulcrum pins, floor wheels, and the floor wheel axles in separated relation.

Fig. 5 is a detail sectional elevation on line 30 5—5 of Fig. 2, showing the swiveling action of the spring in its holder.

The parts will be identified by their numerals of reference which are the same in all the views.

1 is the carpet sweeper case. 2 is the handle bail and 3 is the bail pivot plate secured to the end of the case. 4, 4 are the projecting side bars of the case. 5 is the deflectable end guard bar of thin metal having extensions 51, 51 at each side for attachment to the side bars 4, 4 of the case. The usual deflectable end guard bar is spaced from the end of the case to house the floor wheels and equalizer structure.

6 is the spring support suitably riveted to the guard bar and having a vertical slideway 61 formed at the center. 7 is the spring retained by clip parts 62, 62 on the spring support 6, so that the same pivots freely therein axially. Central offset 71 of spring 7 is disposed between the clips 62, 62 and effectively locates the spring centrally of its support. The support 6 is curved slightly inwardly toward the end of the case.

8, 8 are the floor wheels supported on floating axles 9, 9 supported in enlarged apertures in the end walls of the case in the usual manner.

Equalizing levers 10 and 11 slotted at 101, and

111, are carried by the guard bar 5, being supported by fulcrum pins 12 and 13 which are shouldered and serve also as the connecting rivets for securing the spring support 6 to the guard bar 5. Transverse journal pins 14 and 15 are secured to the outer ends of the levers and engage bearings in the hubs 81, 81 of the floor wheels 8, 8. The inner ends of the levers 10 and 11 contain slotted holes and cooperate with the shouldered brush journal pin 16 which is carried on the slide 10 17 to which it is riveted. The projecting end of the rivet extends into the vertical recess 52 formed by a vertical indentation at the center of the guard bar 5.

Ball bearings in suitable casings 18 embrace 15 each of the hubs 81, 81 and are provided with spring connecting arms 19, 19 which are engaged by offset ends 72, 72 on the spring 7. 20 is the brush, the hub of which is engaged and driven by the floor wheels.

From this description it will be readily seen that when pressure is applied to the carpet sweeper by its operating handle, the floor wheels will yield in equalized relation, due to the presence of the equalizing levers, the spring will act 25 very freely because of its pivotal support at the center, and a very smoothly operating carpet sweeper is thus secured. The pivoting of the spring is indicated diagrammatically in Fig. 5. The spring and equalizer assembly is unitary 30 with the end bar, greatly facilitating its manufacture and making it very convenient to assemble into the completed carpet sweeper. The brush is removable in the usual way by deflecting the thin metal end bars 5 outwardly until the 35 brush pivots are withdrawn.

In this behalf I use the word "equalize" in the sense defined in The Century dictionary as meaning "that which equalizes or makes equal".

My improved structure is capable of very considerable modification while still embodying valuable features of my invention. It is highly effective in its specific form. I desire to claim the specific features of the structure as I have described them in their special relations and I also desire to claim the organization and combination broadly as pointed out in the appended claims.

Having thus described my invention, what I claim as new and desire to secure by Letters Patent is:

1. In a carpet sweeper having at each end a bearing carried by a vertically movable slide, a brush pulley mounted on said bearing, floating floor wheels at each side of and frictionally engaging said brush pulley, and levers each engag-

- ing said movable bearing and the hub of one of said floor wheels; an end member comprising a thin deflectable end bar of uniform cross-section and a center plate secured on the inner face thereof, said center plate having a parallel sided vertical slot therein forming a guide for said slide and an upper portion curled into a horizontal tube adapted to rotatably support a rod spring pivotally connected to said floor wheels.

5 2. In a carpet sweeper having at each end a bearing carried by a vertically movable slide, a brush pulley mounted on said bearing, floating floor wheels at each side of and frictionally engaging said brush pulley, and levers each engaging said movable bearing and the hub of one of said floor wheels; an end member comprising a thin deflectable end bar of uniform cross-section and a center plate secured on the inner face thereof, said center plate having a parallel sided vertical slot therein forming a guide for said slide and an upper portion supporting a rod spring connected to said floor wheels.

10 3. In a carpet sweeper having at each end a bearing carried by a vertically movable slide, a brush pulley mounted on said bearing, floating floor wheels at each side of and frictionally engaging said brush pulley, and levers each engaging said movable bearing and the hub of one of said floor wheels; an end member comprising a thin deflectable end bar and a center plate secured on the inner face thereof, said center plate having a vertical guideway therein for said slide and an upper portion curled into a horizontal tube adapted to rotatably support a rod spring pivotally connected to said floor wheels.

15 4. In a carpet sweeper having at each end a bearing carried by a vertically movable slide, a brush pulley mounted on said bearing, floating floor wheels at each side of and frictionally engaging said brush pulley, and levers each engaging said movable bearing and the hub of one of said floor wheels; an end member comprising a thin deflectable end bar and a center plate secured on the inner face thereof, said center plate having a parallel sided vertical slot therein forming a guide for said guide member, and an upper portion supporting a rod spring connected to said floor wheels.

20 5. In a carpet sweeper having at each end a bearing carried by a vertically movable slide, a brush pulley mounted on said bearing, floating floor wheels at each side of and frictionally engaging said brush pulley, and levers each engaging said movable bearing and the hub of one of said floor wheels; an end member comprising a thin deflectable end bar and a center plate secured on the inner face thereof, said center plate having a parallel sided vertical slot therein forming a guide for said guide member, and an upper portion supporting a rod spring connected to said floor wheels.

25 6. In a carpet sweeper having at each end a bearing carried by a vertically movable slide, a brush pulley mounted on said bearing, floating floor wheels at each side of and frictionally engaging said brush pulley, and levers each engaging said movable bearing and the hub of one of said floor wheels; an end member comprising a thin deflectable end bar and a center plate secured on the inner face thereof, said center plate having a parallel sided vertical slot therein forming a guide for said guide member, and an upper portion supporting a rod spring connected to said floor wheels.

30 7. In a carpet sweeper, the combination of a case having extended side bars and a thin deflectable metallic end guard bar, a central upwardly and inwardly curved spring support carried by the end bar, a removable floor brush disengageable by the deflection of said end bar, floor wheels supported by suitable floating axles to drive said brush, bearing members surrounding the hubs of said wheels and each having a projecting spring arm for spring connection, and a rod spring pivotally supported by the said spring support so that it may pivot axially and having its ends engaging said spring arms.

35 8. In a carpet sweeper, the combination of a case, a deflectable end bar, a central spring support carried by said bar, a removable floor brush disengageable by the deflection of said end bar, floor wheels supported by suitable floating axles to drive said brush, and a straight rod spring pivotally supported by the said spring support so that it may pivot axially with its ends connected to supply pressure to the floor wheels.

40 9. In a carpet sweeper having a brush with brush supporting slide, the combination of the deflectable thin metal end guard bar and a central spring support fastened to and carried by the said guard bar and provided with a vertical guideway for the brush supporting slide.
